ROTARY WING AIRCRAFT

Peter J. Papadakos, St. James, N. Y., assignor to Gyro-dyne Company of America, Inc., Flowerfield, N. Y., a corporation of New York

Application June 24, 1955, Serial No. 36,678

Term of patent 14 years

(Cl. D71—1)

Fig. 1 is a front side perspective view of a rotary wing aircraft, showing my new design.

Fig. 2 is a rear side perspective view of the same.

The aircraft is symmetrical, the opposite side being essentially like the side shown in the drawings.

I claim:

The ornamental design for a rotary wing aircraft, as shown and described.
